VAPOR ELECTRIC DEVICE

Marshall Middleton, Jr., Pittsburgh, Pa., assignor
to Westinghouse Electric Corporation, East
Pittsburgh, Pa., a corporation of Pennsylvania

Application May 7, 1949, Serial No. 92,051

5 Claims. (Cl. 250—27.5)

1

My invention relates to a vapor-electric device and particularly to a lead-in bushing for such a device.

In the construction and maintenance of vapor-electric devices, considerable difficulty has been encountered in providing lead-in bushings for the various electrodes, particularly the anodes which will maintain sufficient vacuum tightness during operation.

It has been difficult to provide a construction which will maintain vacuum tightness and at the same time support the weight of the lead-in conductors as well as the electrodes connected thereto. Not only must the bushings be capable of maintaining the static pressures caused by the weight of the equipment, but also must withstand kinetic pressures due to motion of the device or to electrostatic or magnetic disturbances caused by operation of the device.

It has heretofore been proposed to provide a heavy pressed glass bushing to maintain the mechanical stresses of such a bushing and to seal into the bushing material thin sealing strips which maintain the vacuum tightness. Considerable difficulty has been encountered because of the stresses set up, either during construction of the device or in the mechanical clamping of the bushing to the container of the device.

It is, accordingly, an object of my invention to provide a bushing capable of withstanding stresses not only of construction but of clamping the devices together. Instead of sealing the metal portions into the body of the bushing, I prefer to pressure mold them in place so that the seal between the bushing material and the sealing metals is a portion of the pressure molding operation.

In order to eliminate the clamping stresses, I have provided two clamping surfaces at substantially right angles to each other so that the application of clamping forces is substantially compensated in the device without resulting stress on the material.

Other objects and advantages of my invention will be apparent from the following detailed description taken in conjunction with the accompanying drawing in which:

Figure 1 is a sectional elevation of a vapor-electric device embodying my invention; and

Fig. 2 is an enlarged view of the details of the mechanical clamp and vacuum seal.

In an exemplary embodiment of my invention, the valve comprises a container 1 having a substantially cylindrical wall 2, one end of which is closed by a suitable header 3, preferably me-

2

chanically detachable from the remainder of the container 1 as by bolts 4 although it may be permanently secured as by welding. A cathode pool 5 of vaporizable reconstructable material, usually mercury, is provided in the bottom of the container 1 and an ignition control device, such as a make-alive electrode 6, is arranged in permanent contact with the pool 5 of cathode material and is provided with a suitable lead-in bushing 7 for the application of control potential.

Usually, a pumping connection 8 is provided in some portion of the container 1, preferably a portion remote from the cathode pool 5, to permit ready evacuation of the container 1 and, if desired, the maintenance of such evacuation during the life of the container. If the valve is to be of the pumped type, that is, having evacuation maintained by the application of pumps, it is desirable to provide a mercury shield 9 to prevent droplets of mercury from impinging on the various electrodes in the valve.

In spaced insulated relation to the cathode 5 is a cooperating anode 10, usually constructed of graphite and preferably provided with shields 11 and 12, both of which are also preferably constructed of graphite and supported from the container walls, preferably by insulated supports such as 13 and 14. If desired, the anode shield 11 may be provided with a lead-in connection 15 for the application of control potential to the anode shield 11.

The lead-in conductor 16 for the anode 10 is sealed to the header 3 by means of my improved vitreous seal 20. This seal 20 comprises a substantially cylindrical body portion 21 of relatively great thickness and preferably of pressure molded glass construction.

The cylindrical body portion 21 of the bushing 40 is made as a unitary device by inserting sealing collars or flanges for both the lead-in seal and the container seal into the molds so that when the glass is pressed into position in the mold the sealing metal, both the lead-in collar 33 and the sealing flange 34 are embedded and joined with the vitreous body material so that the construction is substantially unitary. A mechanical clamping flange 35 is provided around the vitreous body 21 and provided with outwardly sloping surfaces 36 and 37 which converge toward the periphery 38 of the flange 35 to provide two opposed clamping surfaces 36 and 37 substantially at right angles to each other. A seating surface 39 of the header 3 is provided which is complementary to the seating surface 37 of the

clamping flange 35 and is generally held in place by a mechanical clamp, usually a clamping ring 40 having a clamping surface 41 complementary to surface 36 so that the stresses applied in clamping the flange 35 to the seating surfaces 39 and 41 are at right angles to each other and substantially cancel out so that no stresses reside in the vitreous body 21 after it is clamped in place.

To provide a seal between the vitreous body 21 and the header 3 of the container 1, the sealing disk 34, which was cast into the periphery of the sealing flange 35, is welded or integrally united to a boss 42 provided on the header 3. By extending outwardly from the periphery of the flange 35 between the clamping surfaces 36 and 37, the sealing disk 34 can be made of sufficient diameter that the heating incidental to welding the disk 34 to the boss 42 is not transmitted to the vitreous body 21 in sufficient quantities to cause warping or cracking. Also, the disk 34 is of sufficient size as to be relatively flexible so that stresses are not readily transmitted by the disk 34 to the vitreous body 21.

The seal between the lead-in conductor 16 and the vitreous body 21 is made by means of the collar 33 embedded in the vitreous material and surrounding an opening 45 in which the lead-in 16 is mechanically locked by any suitable means herein illustrated as an inturned collar or flange 46 on the vitreous body 21 to which the anode stem 16 or conductor is mechanically connected by means of a threaded nut 47 and collar 48 combination. Outside of the mechanical connection, a disk or washer 49 of sealing material is integrally united as by welding or brazing to the lead-in conductor 16, and the exterior periphery of the washer 49 is welded or integrally united to the collar 33 embedded in the vitreous material.

While I have shown a preferred embodiment of my invention and described the same to the best of my present ability, I desire it to be understood that such illustration and description are exemplary only and that changes and modifications can be made therein without departing from the true spirit of my invention or the scope of the appended claims.

I claim as my invention:

1. A lead-in assembly for a vapor-electric device having a metallic container comprising a substantially cylindrical cast vitreous body having a longitudinal passage therethrough, a collar of sealing metal embedded in said body about said passage, a conductor extending through said passage, a mechanical connection retaining said conductor in fixed relation in said passage, a seal

between said conductor and said collar, a seating flange around said body, an annular sealing disk embedded in said flange, the opposed faces of said flange converging toward the periphery thereof, 5 a complementary seat in said container, a clamping ring securing said flange on said seat and a seal between said disk and said container.

2. A lead-in bushing comprising a substantially cylindrical cast vitreous body having a longitudinal passage therethrough, a collar of sealing metal embedded in said body about said passage, an annular seating flange around said body, the opposite faces of said flange converging from the body to the periphery of the flange providing angularly disposed seating surfaces and an annular sealing disk embedded in said flange between said seating surfaces.

3. A lead-in assembly for a metal tank device comprising a tapered annular seat in said tank, a molded vitreous bushing having a passage therethrough, a conductor mechanically secured in said passage, a substantially cylindrical sealing flange cast into said bushing substantially coaxial with the passage, a vacuum seal between said cylindrical flange and the conductor, a seating flange on said bushing, a pair of converging seating surfaces on said flange, a sealing disk cast into said flange between said seating surfaces, a tapered pressure ring mechanically holding said seating flange on said annular seat and a vacuum seal between said disk and said tank.

4. An anode bushing comprising a cast vitreous body having a passage therethrough for receiving a conductor, a collar of sealing metal cast into said body around one end of said passage, a seating flange around said body, the opposed faces of said flange being oppositely sloped to provide oppositely disposed bevel seats and an annular sealing disk cast into said flange and extending beyond the periphery thereof.

5. A lead-in assembly for a metal tank device comprising a cast vitreous insulator having a passage therethrough, a conductor extending through said passage, mechanical means securing 45 said conductor firmly in said passage, a collar of sealing metal embedded in said insulator around said passage, a vacuum seal between said collar and said conductor, a seating flange around said insulator, a tapered seating surfaces on said flange, a complementary seating surface on said tank, clamping means maintaining said seating surfaces in contact, a metal sealing flange embedded in said insulator and sealed to said tank.
